ABSTRACT OF THE DISCLOSURE

A self-winding photographic shutter having a shutter blade system which is influenceable during the exposure run-off by an electronic timing device having an electromagnet and an armature. The armature is caused to make contact with the electromagnet and the timing device is switched on as a function of the actuation of a winding and release lever. The photographic shutter has an over-pull pawl serving to transfer the shutter blade system into a wound position. The over-pull pawl is linked and biased into engagement with the winding and release lever. A driver is provided which is movable with the shutter blade system and causes the armature, mounted on an armature lever, to contact the electromagnet during the winding process. This action also transfers a formed portion of the armature lever, acting as an open time lock, into a locked position. After the wound position has been reached, the driver is held in a fixed position against the armature lever so that the over-pull pawl is enabled to move relative to the winding and release lever against the effect of the over-pull spring, until the shutter blade system is released.

The invention relates to a self-winding photographic shutter with a shutter blade system which is influenceable during the exposure run-off by an electronic timing device having an electromagnet and an armature associated therewith, whereby the armature is caused to make contact with the electromagnet and the timing device is switched on as a function of the actuation of a winding and release lever.

It is an object of this invention to provide a shutter of the above type that is particularly simple in construction requiring a minimum of parts while assuring reliable run-off operation. It has now been found that the foregoing and other objects and advantages can be readily attained in a photographic shutter having an over-pull pawl serving to transfer the shutter blade system into a wound position wherein the over-pull pawl is linked and biased into engagement with the winding and release lever. In addition, a driver is provided that is movable with the shutter blade system and causes the armature, mounted on an armature lever, to contact the electromagnet during the winding process. This action also transfers a formed portion of the armature lever, acting as open time lock, into a locked position.

After the wound position has been reached, the driver is held in a fixed position against the armature lever so that the over-pull pawl is enabled to move relative to the winding and release lever, against the effect of the over-pull spring, until the shutter blade system is released. This simple construction provides for causing the armature to contact the electromagnet so that the part acting as open time lock can release the shutter blade system for run-off at the proper moment during the winding and release process. Special actuating members are not neces-

sary due to the fact that the armature and the lock part are moved by the shutter blade system.

One design of a highly desirable shutter blade system for providing a relatively simple self-winding shutter requiring a minimum of parts in a particularly advantageous manner can be attained according to this invention by having a shutter blade system consisting of two concentrically mounted blades that runoff successively. In this system, the opening blade which runs off first, has a winding arm disposed in the range of motion of the over-pull pawl, and a driver which cooperates with the armature lever during the winding process. The second shutter blade, for ending the exposure, is provided with a projection which, when the shutter blade system is transferred into the wound position, is engaged by the formed portion or projection of the armature lever acting as open time lock. In a further advantageous embodiment of the invention, the arrangement of this formed portion or projection in relation to the rotational axis of the armature lever is such that the shutter blade is able to move the armature lever to the side when the electromagnet is currentless, thus eliminating the use for a special return spring for the armature lever.

To further perfect the invention toward the end of achieving reliable operation of the electronic timing device which cooperates with the shutter blade system, the invention further provides a short-circuit switch for the electronic timing device that enables a capacitor of this device to charge. The short-circuit switch is so disposed in the range of motion of the over-pull pawl that this switch is opened after release of the shutter blade system by the over-pull pawl under the effect of the over-pull spring following the motion of the winding and release lever.

In another embodiment of this invention additional structural simplification of the shutter arrangement may be achieved by providing a leaf spring instead of the over-pull pawl and over-pull spring.

Various other objects, features and advantages of this invention will be apparent from the following specification, claims and the drawing appended hereto wherein:

FIGURE 1 is a top view of the self-winding shutter of this invention in its normal position with an electronic timing device illustrated schematically.

FIGURE 2 is a view illustrating the shutter of FIGURE 1 without the schematically illustrated electronic timing device showing the parts in the position assumed after transfer of the shutter blade system into the wound position.

FIGURE 3 is a view similar to FIGURE 2 illustrating the shutter in open position, wherein the over-pull pawl, released with the release of the shutter, has opened the charge starting contact of the electronic timing device.

Referring now in detail to the drawings, a plate, designated by reference numeral 1, carries the essential shutter parts of a photographic shutter designed to be self-winding. A shutter blade system, illustrated in its normal position in FIGURE 1, is disposed on the plate 1, serves to cover an exposure aperture 1a machined into plate 1. The shutter blade system is formed of two shutter blades 2 and 3 which runoff successively so that blade 2 opens the aperture 1a after release and the second shutter blade 3 follows the other blade after the elapse of a certain exposure time to again close the exposure aperture 1a. Cooperating with each of the shutter blades 2 and 3 are drive springs 4 and 5 biased against pins 7 and 8, respectively on the blades 2 and 3. The blades are designed as segment-like blades and are mounted on the same axis on a pin 10 fastened to the plate 1. In the normal position illustrated in FIGURE 1, the opening blades 2 is biased by the drive spring 4 against a fixed pin 12 while the pin 8 of the

closing blade 3 is biased against the edge of the opening blade 2 by the drive spring 5.

In order to cock the two springs 4 and 5, a spring loaded winding and release member 15, designed in the disclosed embodiment as a two-armed lever, is pivotally mounted on the plate 1 by means of a pin 14. One arm 15a provides a means for actuating the winding and release lever 15, and the other arm 15b is linked to an over-pull pawl 17 in the form of a one-armed lever which is biased into contact with a pin 19 of the winding and release lever 15 under the force of an over-pull spring 18. The over-pull pawl 17 cooperates with the opening blade 2 which is provided with a winding arm 2a for engagement with a tab 17a of the over-pull pawl 17 in order to transfer the shutter blade system into the wound position during the winding and release motion.

As may be seen further from the drawings, the shutter blade system 2, 3 cooperates with an armature lever 21 for the achievement of varying exposure times. The lever 21 is pivotally mounted on the plate 1 and carries an armature 22 which cooperates with an electromagnet 23 controlled by an electronic trip circuit. In detail, the arrangement is such that the armature 22 is caused to make contact with the electromagnet 23 by the shutter blade system 2, 3 during the winding motion. For this purpose, a projection 2b is provided on the opening blade 2 for cooperation with a striking tab 21a disposed on the armature lever 21 in order to position the armature lever. An additional stop 21b also disposed on the armature lever 21, serves as open time lock and positions itself in front of a knob 3a of the closing blade 3 when the armature 22 makes contact with the electromagnet 23 thereby holding the closing blade 3 in the open position as long as current flows through the electromagnet.

The trip circuit serving to control the electromagnet 23 consists essentially of two emitter-coupled transistors T₁ and T₂, a capacitor C, a photo resistor 26 and a battery 27 for supplying current. In place of the photo resistor 26, an infinitely variable resistor or several gradated fixed resistors and a setter serving for setting a certain resistance value may also be provided. The connection of the electronic trip circuit with the battery 27 is established by a switch S₁ having a contact tongue 28 which is transferred into a contact making position by a projection 15c on the winding and release lever 15 at the end of the winding process, expediently after the armature 22 has made contact with the electromagnet 23. An additional switch S₂ forms part of the trip circuit and bridges the capacitor C in the normal position of the shutter and is opened advantageously by the over-pull pawl 17 under increased spring pressure after the release of the shutter blade system. In detail, the arrangement is such that the over-pull pawl 17 is provided with a projection 17b which strikes against the contact tongue 30 of the switch S₂ and opens it under the effect of the cocked over-pull spring 18 after release of the shutter blade system 2, 3.

The operation of the above described shutter arrangement illustrated in the drawings is as follows:

When the winding and release lever 15 is actuated, the over-pull pawl 17 first moves clockwise in the manner of a lever rigidly joined to the winding lever through which motion the two shutter blades 2 and 3 are turned counterclockwise about the bearing pin 10 due to the fact that the tab 17a engages the winding arm 2a, thereby putting the drive springs 4 and 5 under increased tension and keeping the shutter aperture 1a closed. At the end of the winding process, the projection 2b of the opening blade 2 strikes against the tab 21a of the armature lever 21, and pivots it in a counterclockwise direction until the armature 22 makes contact with the electromagnet 23. In this phase of the operation, as shown in FIGURE 2, the locking stop 21b disposed on the armature lever 21 has simultaneously positioned itself in front of the knob 3a of the closing blade 3. In further moving the winding and release lever 15, it travels an excess distance, whereby the over-pull pawl 17 turns relative to the lever 15, in-

creasing the tension of the spring 18, due to the fact that the opening blade 2 is disposed firmly against the armature lever 21. The excess distance that the lever 15 moves is utilized to provide positive engagement of armature 22 with the electromagnet 23 and also to close the switch S₁ by means of the projection 15c on the winding and release lever 15 as illustrated in FIGURE 2. Consequently, the electronic trip circuit is connected by the battery 27 so that the electromagnet 23 receives current via the transistor T₂ while transistor T₁ remains blocked. Finally, at the end of the winding and release motion, the over-pull pawl 17 disengages from the winding arm 2a of the opening blade 2 which returns under the influence of its drive spring 4 into the starting position fixed by pin 12, thereby opening the exposure aperture 1a, while the closing blade 3 is held in the open position by the locking stop 21b. With the release of the opening blade 2 by the over-pull pawl 17, the pawl 17 follows the motion of the winding and release lever 15 under the effect of the cocked over-pull spring 18 until it strikes pin 19, whereby the projection 17b strikes against the contact tongue 30 of switch S₂, opening it as shown in FIGURE 3, which results in the charging of the capacitor C.

When the capacitor C has reached the base potential of transistor T₁ in a time span depending on the resistance value of the photo resistor or of a manually variable resistor, it conducts while transistor T₂ is suddenly blocked. This immediately causes the electromagnet 23 to become currentless so that the closing blade 3 under the effect of its spring 5, is enabled to turn the armature lever 21 clockwise thereby pushing the locking stop 21b to the side and returning to the closed position. This return motion of the closing blade 3 can take place practically simultaneously with the collapse of the magnetic field in the electromagnet 23 because no self-retardation occurs due to the special configuration of the armature lever 21, the locking stop 21b and the knob 3a of the closing blade 3 whereby the locking stop 21b may be positioned advantageously between the pivot point of the armature lever 21 and the knob 3a of the closing blade 3 and also due to the relatively small mass to be moved.

It will be understood that the foregoing description with the details of exemplary structure is not to be construed in any way to limit the invention, but that modifications may be made thereto without departing from the scope of the invention as set forth in the following claims.

Having thus described our invention, we claim:

1. A self-winding photographic shutter comprising: a shutter blade system; a winding and release lever; an electronic timing device having an electromagnet and a cooperating armature influencing said shutter blade system during the exposure run-off, wherein said armature contacts the electromagnet and said timing device is switched on upon actuation of said winding and release lever, an over-pull pawl linked with said winding and release lever and biased into engagement therewith during the cocking movement by an over-pull spring, said pawl engaging said shutter blade system and transferring the latter into a wound position when the cocking and release lever is actuated, whereby biasing means for said shutter blade system is cocked; an armature lever movably mounting said armature, said armature lever having a projection thereon; and a driver movable with said shutter blade system, said driver being operably connectable with said armature lever to cause the said armature to make contact with said electromagnet during the winding process and to transfer said projection on said armature lever into a position in which the projection prevents the shutter blade system from closing the shutter opening, and wherein, after attainment of the wound position, said driver is held in a fixed position against said armature lever enabling said over-pull pawl to move relative to the winding and release lever against the effect of said over-pull spring until said shutter blade system is released.

2. The photographic shutter of claim 1 wherein said shutter blade system has an opening blade and a closing blade concentrically mounted for successive running off; said opening blade adapted to run off first, having a winding arm disposed in the range of motion of said over-pull pawl and wherein said opening blade supports said driver for engagement with said armature lever during the winding process; said second closing blade, adapted to end the exposure, having a projection for engaging said projection of said armature lever which positions itself adjacent thereto during the transfer of the shutter blade system into the wound position.

3. The photographic shutter of claim 2 wherein said armature lever is configured so that said projection is a formed portion positioned in relation to the rotational axis of said armature lever in such a manner that said closing blade is enabled to push said armature lever to the side when said electromagnet is currentless.

4. The photographic shutter of claim 1 wherein said electronic timing device has a short-circuit switch and a capacitor which is chargeable upon actuation of said short-circuit switch, said short-circuit switch being disposed in the range of motion of said over-pull pawl so that it is opened by said over-pull pawl following the motion of said winding and release lever under the effect of said over-pull spring after the release of said shutter blade system.

5. The photographic shutter of claim 1 wherein said over-pull pawl and said over-pull spring are in the form of a leaf spring.

6. A self-winding photographic shutter comprising: shutter blade means; winding and release means operably connected to said shutter blade means; electronic timing means connected to said shutter blade means; electronic timing means having a cooperating armature and electromagnet controlling said shutter blade means during exposure runoff, said winding and release means being operable to cause said armature to contact said electromagnet and to cause said timing device to be switched on; an over-pull pawl pivotally mounted on said winding and release means and biased into engagement therewith by over-pull biasing means, said pawl being operably connected to said shutter blade means for transferring said shutter blade means into a wound position; a pivotally mounted armature lever supporting said armature, said lever having engaging means thereon; and a driver on said shutter blade

means supported for movement therewith, said driver being connectable with said armature lever to cause said armature to make contact with said electromagnet during the winding process and to transfer said engaging means on said armature lever, which engaging means act as an open time lock, into a locking position, and wherein after attainment of the wound position, said drive is held in a fixed position by said armature lever enabling said over-pull pawl to move relative to the winding and release means against the effect of said over-pull biasing means until said shutter blade means is released.

7. The photographic shutter of claim 6 wherein said shutter blade means has an opening blade and a closing blade coaxially mounted for successive run-off; said opening blade being adapted to run-off first and having a winding arm disposed in the range of motion of said over-pull pawl, said opening blade supporting said driver so that said driver is engageable with said armature lever during the winding process; and wherein said closing blade, adapted to end the exposure, is connectable with said engaging means on said armature lever which positions itself adjacent thereto during the transfer of the shutter blade means into the wound position.

8. The photographic shutter of claim 7 wherein said armature lever is configured so that said engaging means is a formed portion positioned relative the rotational axis of said armature lever so that said closing blade is enabled to move said armature lever out of the way when said electromagnet is currentless.

9. The photographic shutter of claim 6 wherein said electronic timing means has a short circuit switch and a capacitor which is chargeable upon actuation of said short-circuit switch, said short-circuit switch being disposed in the range of motion of said over-pull pawl so that it is opened by said over-pull pawl under the effect of an over-pull spring following the motion of said winding and release means after the release of said shutter blade means.
